UNITED STATES PATENT OFFICE.

FRANK C. AYER, OF COLUMBUS, OHIO.

VEHICLE-DASH FASTENING.

SPECIFICATION forming part of Letters Patent No. 271,017, dated January 23, 1883.

Application filed October 16, 1882. (No model.)

To all whom it may concern:

Be it known that I, FRANK C. AYER, a citizen of the United States, residing at Columbus, county of Franklin, and State of Ohio, 5 have invented new and useful Improvements in Vehicle-Dash Fastenings, of which the following is a specification.

My improved dash-fastening is adapted for use with a frame having short feet forged with 10 or welded to the lower bar, as in the patent of Lance and Elliot, of August 29, 1882; and the object of my improvement is to provide a fastening adapted for such integral feet in the dash-frame of a phaeton, surrey, or buggy, 15 which have no solid front to bolt through, as required by the fastening shown in such patent.

In the drawings hereunto annexed I have illustrated in Figure 1 my improved dash-fastening as applied to a portion of a covered dash-frame and to a portion of the frame of what is 20 known as a "bracket" front vehicle-body; Fig. 2, a vertical section of the same; Fig. 3, a portion of the dash-frame with its short integral foot, and Fig. 4 the foot-fastening.

The dash-frame has short feet *a* welded or forged with its lower bar near each end. That portion *b* of the foot which joins the bar is in 25 oblique line with the frame, and extends downward a sufficient distance to allow the leather covering to be stitched along the lower edge of the bar, without obstructing the operation of the sewing-machine, by reason of the lateral projection of the foot below its joining with said bar. This lateral projection forms a shoulder, *c*, which stands out from the inner front 30 of the frame, from which the foot extends down parallel with the dash-frame, so as to stand between the lower part of the dash-leather and the front edge of the vehicle-body front, to 35 which said integral foot is secured by a separate foot bolted to the body-frame and to said integral foot. This separate foot is a flat bar, *d*, formed with a shoulder, *e*, at its front end, 40 adapted to fit upon the shoulder *c* of the integral foot, and having an end bearing part, *f*, below its shoulder, adapted to fit against the integral foot *a* below its shoulder. The shoulder end of the separate foot is enlarged to 45 give the face and shouldered bearings. This

separate foot is bolted to the upper surface of 50 the side bar of the body-front, and a bolt, *g*, secures it to the integral dash-foot. The head of this bolt is flat enough to lie between the lower part of the dash leather and the dash-foot, through a slot, *i*, in which said bolt passes, 55 and, passing up through the said body-bar and the separate foot, is secured by a nut, *n*, on its upper end.

I prefer to use a curved bolt, as shown, because it may be comparatively short, and to 60 seat its fastening-nut upon an inclined top portion of the separate foot; but a straight bolt might be used, passing obliquely through the body-front and the feet below their shouldered joining. This construction clamps the dash-frame firmly against the front edge of the body-front and against the shouldered ends of the 65 separate feet, and allows the dash to be applied to the body-front finished, with the separate feet as fixtures. This construction allows the dash-frame to be adjusted laterally 70 upon the separate feet-fastenings by means of the horizontal slots in the integral feet, which should be wide enough for such adjustment and to maintain the shouldered bearings in 75 such adjustment.

It will be understood that the bolt passing obliquely through the three joined parts—that is to say, the front end of the side bar, *B*, of the body-front, the flat front end of the separate 80 foot *d*, and the foot *a* of the dash-frame—gives a clamping action of the bolt obliquely across the three joined parts, binding the shouldered bearing-surfaces of the metal feet firmly together and the dash-frame feet firmly against 85 the body-front. This method of fastening a dash and the construction by which the fastening is effected is the improvement which I claim.

I claim—

1. The fastening device for a vehicle-dash herein described, consisting of the dash-feet *a*, formed with an offset bearing-surface or shoulder, *c*, at the junction of said feet with the frame, separate flat feet *d*, having each an offset bearing or shoulder, *e*, at its upper front end, and a bolt, *g*, passing obliquely through the three joined parts *a d D* below the lapping 95

bearings *c e*, whereby to adjust and fasten the dash-frame to the body-front, substantially as described.

2. The combination, with the body-front *D* and the separate flat feet *d*, having offset bearings or shoulders *e* at the upper front end, of the dash-frame, having feet shouldered at the junction *c* with said frame, and the bolt *g*, passing through the metal and the body-joined parts, substantially as described.

In testimony whereof I have hereunto set my hand in the presence of two subscribing witnesses.

FRANK C. AYER.
